United States Patent Office.

SAMUEL DOUGLASS, OF KALAMAZOO, MICHIGAN.

Letters Patent No. 102,785, dated May 10, 1870.

FIRE-TONGS.

The Schedule referred to in these Letters Patent and making part of the same

To all whom it may concern:

Be it known that I, SAMUEL DOUGLASS, of Kalamazoo, in the county of Kalamazoo and State of Michigan, have invented a new and useful Improvement in Tongs; and I do hereby declare that the following is a full and exact description of the same, reference being had to the accompanying drawings and to the letters of reference marked thereon.

This invention has for its object the production of a pair of tongs which shall be capable of serving other useful purposes besides those for which they are ordinarily employed, without materially increasing the cost of producing the same, and consists mainly in continuing the legs of the tongs above the joint which connects them, and in so forming their upper ends that they are adapted for the purposes desired.

To enable others skilled in the art to make and use my invention, I will now proceed to fully describe the construction of the same.

A A' represent the legs of the tongs, which may be constructed in any suitable manner. These legs are continued beyond the joint B, by means of which they are connected together in any of the well-known ways,

and are formed at their upper ends into such shapes as will adapt them for the use desired of them.

In the drawings, the upper end of the part A is formed into a hook, which may be advantageously used for lifting vessels from the fire, and for other similar purposes.

The upper end of the part A' is slightly curved, in order to adapt it for lifting the covers of stoves, &c.

The described implement may be constructed at a small cost, and is well adapted for the various uses for which it is intended.

Having thus fully described my invention,

What I claim as new, and desire to secure by Letters Patent of the United States, is—

The tongs described, consisting of the parts A A', when constructed and united as described, for the purpose set forth.

This specification signed and witnessed this 11th day of March, 1870.

SAMUEL DOUGLASS.
